UNITED STATES PATENT OFFICE

THOMAS F. CROCKER, OF CHICAGO, ILLINOIS, ASSIGNOR TO RESERVE HOLDING COMPANY, OF KANSAS CITY, MISSOURI, A CORPORATION OF DELAWARE

TELEPHONE SYSTEM

Application filed March 4, 1927. Serial No. 172,582.

The present invention relates to telephone systems in general, but is concerned more particularly with telephone systems containing both manual and automatic offices.

5 The broad general object of the invention is the provision of novel arrangements in connection with trunk lines from manual offices to automatic offices for associating the calling devices with trunk lines over which automatic 10 switches are to be operated to complete the connections. The invention is particularly applicable to systems in which plugs and jacks are provided to associate calling devices with trunks.

15 One object of the invention is the provision of a calling device circuit in which the impulse circuit is normally open and cannot be closed unless the trunk line with which the calling device circuit is connected is idle, this 20 arrangement being provided to avoid interference at a multiple switchboard.

25 It is a further object to give the operator a visual busy signal to indicate to her when the trunk line with which her calling device circuit is connected is busy.

According to a feature of the invention, a test conductor for the calling device circuit is provided having two branches, one branch being connected to a test relay, and the other 30 branch being connected to a guarding source of potential, with means under the control of the test relay for transferring the test conductor from the test relay branch to the other in case the test relay does not encounter a 35 guarding potential on the test conductor.

According to another feature of the arrangement, the switch control circuit is maintained open in a trunk line until the operator has turned her calling device off normal 40 thereby guarding against the possibility of preliminary impulses when the operator plugs in either at the line jack or at the dial jack of a trunk line.

45 Another object of the invention is the provision of arrangements for automatically transferring the switch control circuit to the calling device circuit when the calling device is turned off normal and for transferring the 50 circuit back to a holding bridge in the trunk either when the operator removes the dialing

plug from the dialing jack or when the called man responds, in case the calling device circuit is left in association with the trunk line.

Another object of the invention is to provide means for placing a guarding potential 55 on the test conductor of the dialing multiple so as to guard the trunk line against intrusion by other dialing circuits as long as the trunk line is in use and after the dialing circuit used to set up the connection has been 60 disassociated from the trunk line.

It is a further object of the invention to provide an arrangement for enabling the calling subscriber to hear any tone signals 65 encountered by the automatic switches during the process of setting up the connection, while the calling device is associated with the trunk.

A further object of the invention is to provide, in connection with a two-way simplex 70 dialing trunk line, an arrangement whereby the simplex dialing and supervising circuit is normally open so as to permit a ringing response device to operate over the trunk line when a call comes in, and is closed when the operator plugs in to permit dialing and supervising 75 to be carried out over the simplex circuit.

According to a further feature of the invention, the simplex circuit has been arranged 80 so that the switch control circuit is transferred to the calling device circuit only while the calling device is actually off normal, thereby preventing any danger of preliminary impulses when the calling device plug is being inserted into the dial jack.

Referring now to the accompanying drawing, Fig. 1 shows a one-way trunk line TL^1 outgoing from a manual board of the multiple type to an automatic office in which the automatic switches are operated over a loop circuit. The trunk circuit TC^1 is interposed between the line jack LJ^1 and the dial jack DJ^1 and the trunk line to perform certain switching operations to be hereinafter explained. To the left of the dial jack DJ^1 there is provided a dial cord terminating in the dial plug P^1 and having certain relays and the calling device (dial) CD^1 associated therewith. This dial cord is located at an operator's position, a similar cord being provided at each of the 100

other positions of the multiple board. The busy lamp 101 is associated with the busy relay 102 so as to give the operator a visual busy signal in case the dial jack in which the plug P^1 is inserted tests busy.

5 In Fig. 2, the trunk line TL^2 is shown outgoing from a manual switchboard to an automatic office in which the switches are operated over the two conductors of the trunk line in 10 multiple and a ground return. The line jack LJ^2 and the dial jack DJ^2 associated with the trunk line TL^2 are not multiplied to any other 15 positions of the switchboard. As a result, no busy testing arrangement is necessary in connection with the dial cord terminating in the plug P^2 .

For a disclosure of the automatic switches which will operate in conjunction with the trunk line TL^2 , reference may be had to the 20 copending application of Norman H. Saunders, Serial No. 153,791, filed December 10, 1926. The cord circuit used at the switchboards in the present application may be of the well known common battery type, a suitable 25 cord circuit being shown in the above-mentioned Saunders application.

Regarding the automatic switches operated over the trunk line TL^1 , these switches may be of the well known two-wire type, the connector switches being arranged to reverse the current flow in the trunk line when the called man responds. Such switches are shown in Patent 1,614,678.

The invention having been described generally, a detailed description of the operation of the apparatus shown will now be given. For this purpose, it will be assumed that the operator at the switchboard shown in Fig. 1 tests the sleeve of the line jack LJ^1 with the 35 tip of her cord and finds the trunk line idle. The operator thereupon inserts the plug of her cord into the jack LJ^1 , whereupon relay 105 operates over the sleeve of the plug and jack in series, preparing circuits for relays 40 106, 107, and 109. It will be noted that the bridge across the tip and ring of the jack LJ^1 , including the upper winding of relay 106 is open at the contacts of relay 107. Accordingly, the supervisory lamp in the operator's 45 cord circuit is enabled to remain lighted over the sleeve circuit. The operator now places the plug P^1 of the dialing cord into the dial jack DJ^1 . Since the operator has just tested the trunk line with the tip of her plug and 50 found it idle, the dial jack DJ^1 will test idle and the busy relay 102 will not operate. Therefore, no relay operation takes place when the plug P^1 is inserted into the dial jack.

The operator now turns the calling device 55 CD^1 in accordance with the first digit in the desired number. As soon as the dial of the calling device moves off normal, a circuit is closed at the off-normal contacts thereof for the upper winding of the relay 103 through 60 the armature, normal, of relay 102. Relay

103 prepares the impulse circuit at its inner armature, and at its lower armature disconnects the test conductor (the ring conductor) of the plug P^1 from test relay 102 and connects it to the lower winding of relay 103, 70 thereby placing battery on the ring of the plug and jack through the lower winding of relay 103. This closes a circuit through the upper armature, normal, of relay 106 for the marginal transfer relay 109 through the lower armature of relay 105 to ground. Relay 109 75 operates over this circuit and closes a locking circuit for itself at its inner upper armature independent of the upper armature of relay 106. At its upper and lower armatures, relay 109 connects the outgoing tip and ring trunk conductors to the tip and sleeve, respectively, of the dial jack DJ^1 , the connection to the sleeve conductor including the lower winding of induction coil 108 for a 80 purpose to be pointed out hereinafter. The outgoing trunk conductors are thus connected to the prepared bridge in the dial cord including the tip and sleeve conductors of the plug P^1 , inner armature of relay 103, contacts of the release key, polarized relay 104, and the 85 impulse springs of the calling device CD^1 . When this circuit is closed the automatic switch to which the trunk line TL^1 extends is prepared for operation in the usual manner. Relay 104, being correctly polarized, does not 90 operate at this time.

In the trunk circuit TC^1 , as a further result of the operation of relay 109, a circuit is 95 closed at its inner lower armature for the lower windings of relays 106 and 107 in multiple. Relay 106 operates at this time but the electro-polarized relay 107 does not 100 operate. Upon operating, relay 106 closes at its lower armature a locking circuit for its 105 lower winding through the inner armature of relay 105. At its inner upper armature, relay 106 closes a bridge including the upper winding of relay 107 and the upper winding of induction coil 108 across the disconnected 110 talking conductors to the right of the talking condensers so as to provide a holding circuit for the automatic switches after relay 109 falls back. At its upper armature, relay 106 115 opens the initial circuit of the relay 109, leaving relay 109 operated through its inner armature, and connects the test conductor to battery through the high resistance 110 so as to maintain the test contact of the dial jack DJ^1 busy as long as the plug of the calling 120 cord circuit is in line jack LJ^1 .

As the calling device CD^1 returns to its 125 normal position, the impulse circuit is interrupted at the impulse springs of the calling device a number of times depending upon the forward position to which the dial of the calling device was advanced. When the normal position of the calling device is again reached, the off-normal contacts of the calling device open the circuit through the upper winding 130

of relay 103, but relay 103 remains operated through its lower winding in a circuit previously traced through relay 109 of the trunk circuit TC^1 .

5 When the operator again turns her calling device CD^1 , the off-normal springs again close, but without any particular utility at this time as relay 103 is already operated. The impulsing circuit is again opened the required number of times by the impulse contacts of the calling device as the dial returns to its normal position.

10 After the operator has dialed the complete number, the circuits remain in the same condition until the operator removes the plug P^1 from the jack DJ^1 , or until the called man responds. It will be assumed first for the sake of illustration that the operator has received another call before the first called man has responded and that she has need of the dial cord to set up another automatic connection. In this case the operator pulls the plug P^1 from the jack DJ^1 . When the plug is removed, the bridge across the conductors of the 15 trunk line TL^1 is opened at the tip and sleeve contacts, and the initial circuit for relay 109 through the lower winding of relay 103 is opened at the ring contact of the plug and jack. A circuit for relay 109 now exists 20 through the upper armature, operated, of relay 106 and the inner upper armature of relay 109. Relay 109, however, being marginally adjusted is unable to remain operated in series with the relatively high resistance 110, and 25 quickly falls back, transferring the outgoing trunk conductors to the local bridge including the inner upper armature of relay 106, upper winding of relay 107 and the upper winding of the induction coil 108. This 30 transfer is made by relay 109 very quickly and the established connection is not released. It may occur, however, that the line relay of the connector in use falls back momentarily, but this does not cause any further movement 35 of the connector wipers for reasons well known. Current is now flowing through both windings of relay 107, but the relay is not operated owing to the direction in which the relay is polarized.

40 It will now be assumed that the operator does not receive another automatic call right away and that she accordingly leaves the plug P^1 in the dial jack DJ^1 . Under this condition, if the called line is busy, busy tone 45 current flows over the trunk line conductors from the operated connector and through the dial cord. These tone currents are repeated at the induction coil 108 into the prepared holding bridge, with the result that the calling subscriber hears the busy signal. Assuming now that the called line is idle, the 50 polarized relay 104 is operated when the reversal of current takes place when the called man responds. Upon operating, relay 55 104 applies ground to the ring conductor of

the plug P^1 , short circuiting relay 109 in the trunk circuit TC^1 . Relay 109 lets go and transfers the outgoing trunk conductors to the local bridge including the upper winding of relay 107. At its inner upper armature, 70 relay 109 disconnects itself from the ring conductor of the dial jack, the upper armature of relay 106 being in an operated condition.

75 Responsive to the disconnection of the outgoing trunk conductors from the bridge including the polarized relay 104 of the dial cord, relay 104 falls back and removes ground from the ring conductor of the plug P^1 whereupon relay 103 falls back and transfers 80 the ring conductor to the test relay 102. When this takes place, relay 102 operates in series with the resistance 110 in the trunk circuit TC^1 which is connected to the ring contact of the dial jack through the upper armature of relay 106. Relay 102 opens a point in the circuit of relay 103 and closes a circuit 85 for the busy lamp 101.

90 In the trunk circuit TC^1 the electro polarized relay 107 operates responsive to the transfer of the holding circuit to the bridge including its upper winding, as the current reversal has already taken place. Upon operating, relay 107 closes a bridge across the tip and ring conductors of the jack LJ^1 including the upper winding of relay 106. When this occurs, the supervisory relay in 95 the common battery cord circuit operates over the tip and ring conductors of the jack LJ^1 and extinguishes the calling supervisory 100 lamp. The calling and called subscribers may now converse with each other in the usual manner.

105 When the conversation has been terminated, the two subscribers replace their receivers. 105 When the receiver is replaced at the automatic substation, the connector in use reverses the current flow in the conductors of the trunk line TL^1 back to normal, whereupon the electro polarized relay 107 in the 110 trunk circuit TC^1 falls back and opens the bridge across the talking contacts of the jack LJ^1 . When this occurs the supervisory relay in the cord circuit falls back and permits the associated supervisory lamp to light as a disconnect signal.

115 When the operator removes the plug from the jack LJ^1 , relay 105 falls back and opens the locking circuit of relay 106 and the circuit of the lower winding of relay 107. Relay 106 120 falls back and opens the holding bridge at its inner upper armature and removes the guarding potential from the ring contacts of the dial jack DJ^1 . The automatic switches release as a result of the opening of the holding bridge.

123 In the dial cord, the busy relay 102 falls back when the guarding potential is removed from the ring conductor by relay 106. The lamp 101 thereupon becomes extinguished. 129

In case the operator receives another call to be completed over the trunk line TL^1 before this trunk line is taken for use by another operator at one of the multiples of the line jack LJ^1 , the operator may plug in the line jack LJ^1 and start dialing her number right away without performing any busy test as the unlighted condition of the lamp 101 indicates to her that the trunk line is idle. 10 It may happen, however, that two operators will plug in at the line jack multiple before either of them causes the dial jack multiple to be made busy by turning her calling device off normal. In this case, when the first operator to operate her calling device makes the calling device multiple busy, the relay corresponding to relay 102 becomes operated in the second dial cord, causing the lamp corresponding to the lamp 101 to become lighted and preventing the operation of the transfer relay corresponding to relay 103. For this reason, if two operators start to turn their dials at about the same time the unsuccessful operator will note that her busy lamp corresponding to lamp 101 becomes lighted and she will cease to dial and take another trunk. It will be noted that the loop is not closed in the dial cord of the unsuccessful operator because relay 103 of the unsuccessful cord is 20 prevented from operating.

In order to handle the traffic efficiently at night, the operators are withdrawn from duty as the traffic becomes lighter and lighter, and there is in many installations only one 25 operator on duty during several hours at night. At such times, there may be occasional rises in traffic until the calls come in faster than one operator can conveniently handle them, but this usually lasts for only a few minutes with the result that the night operator can eventually dispose of all the waiting calls. During such busy periods, the night operator is able to take a short cut, so to speak, in handling a connection which 30 consists in starting to turn the dial of the calling device CD^1 at the same time that she takes a hold of the plug P^1 , Fig. 1, to insert it into a dial jack, such as the dial jack DJ^1 . It is permissible for her to do this during the night since no other operator is working and the busy-test arrangements in the dial cord are, therefore, of no utility at this time.

With the calling device CD^1 off-normal at the time the plug P^1 is inserted into a jack 55 (the jack DJ^1 , for example), relay 103 is operated and a battery potential through the lower winding thereof appears on the ring conductor of the plug P^1 , operating relay 109 as soon as the plug is fully inserted into the 60 jack. Under this condition, it is particularly advantageous to employ the ring conductor instead of the sleeve conductor for the energization of relay 109, because the ring contact of the plug is the last contact of the plug to 65 close with the corresponding contact of the

jack, and it does this just before the plug is fully inserted and after the other two contacts of the plug are in engagement with the corresponding contacts of the jack. If the conductors of the plug P^1 and the jack DJ^1 were connected up in the normal way with the testing operation and the operation of relay 109 carried on over the sleeve conductor, there would be the danger of preliminary impulses upon the insertion of the plug P^1 into jack DJ^1 , especially in the case of worn plugs or jacks, on account of the likelihood of relay 109 dropping back one or more times after it is pulled up following a partial or hesitant insertion of the plug into the jack. 70 In addition to the likelihood of causing preliminary impulses, objectional clicking in the talking circuit extending back to the calling subscriber is caused by the chattering action of relay 109 in case such action occurs. With the arrangement as shown, however, there is no chattering action of relay 109 as this relay does not operate until the plug is practically 75 fully seated in the jack. 80

Referring now to Fig. 2, the arrangement shown therein will be described. For this purpose it will be assumed first that a call is received over the trunk line TL^2 from the automatic office. When the connection is completed to the trunk line TL^2 in the automatic office, ringing current is projected over the two conductors thereof, operating relay 206, whose upper winding is bridged around the condenser between the two right-hand repeating-coil windings. Relay 206 closes a 90 locking circuit for its lower winding at its inner armature, and at its lower armature 95 closes a circuit for the lamp 201.

When the operator notes the lighted condition of the lamp 201, she inserts an answering plug into the line jack LJ^2 . When the plug is fully inserted, a circuit is closed over the tip and ring contacts of the jack and through the left-hand repeating-coil windings for relay 203. Relay 203 operates and 100 places ground on the lower terminal of sleeve relay 202. Relay 202 operates and closes a locking circuit for itself independent of relay 203, at the same time opening the locking 105 circuit of relay 206. Relay 206 now falls back and the lamp 201 becomes extinguished. 110 At its upper armature, relay 202 shunts the condenser associated with the right-hand repeating-coil windings, and at its inner upper armature it places ground on the upper terminal of supervisory relay 205, thereby applying a ground potential through inner contacts of relay 204 to both conductors of the 115 trunk line TL^2 . This application of ground potential results in the removal of the source of ringing current in the manner explained in the Saunders application hereinbefore referred to. Relay 205, however, does not become operated at this time. As a result the 120 125 130

operator receives dark supervision in the answering end of her cord circuit.

The operator now completes the connection to the desired subscriber in the usual manner.

When the conversation is over the two subscribers replace their receivers. When the automatic subscriber replaces his receiver, the automatic switches release and the supervisory relay 205 becomes operated owing to the placing of an operating potential on the two conductors of the trunk line TL^2 in the automatic exchange as disclosed in the above-mentioned Saunders application. When relay 205 operates it opens the bridge across the tip and ring contacts of the jack LJ^2 , whereupon relay 203 in the trunk circuit TC^2 and the answering supervisory relay in the cord circuit fall back. The operator is thereby given a disconnect signal and she pulls down the connection. When the connection is pulled down, relay 202 falls back and opens the circuit of relay 205 whereupon relay 205 restores.

Assuming now that the operator receives a call for a connection to be set up over the trunk line TL^2 , she inserts the calling plug of a cord circuit into the line jack LJ^2 , whereupon relay 203 operates as before and connects up the sleeve relay 202. Relay 202 operates as before, closing a locking circuit for itself at its lower armature, shorting the right-hand condenser associated with the repeating coil windings, and placing ground on the upper terminal of relay 205. As the conductors of the trunk line TL^2 normally extend to battery in the automatic exchange, relay 205 operates over the two conductors of the trunk line TL^2 in parallel and opens the bridge across the tip and ring conductors of the line jack LJ^2 so as to cause the supervisory lamp in the operator's cord to become lighted. The closure of the circuit over the trunk line including relay 205 results in the preparation of the apparatus in the automatic office to respond to the impulses.

The operator now inserts the plug P^2 into the dial jack DJ^2 . It will be noted that no relay operation takes place as a result of the mere insertion of the plug into the jack, thereby avoiding any possibility of preliminary impulses due to careless or hesitant insertion of the plug P^2 into the jack.

When the operator turns the calling device off normal, a circuit is closed over the tip of the plug and jack for the transfer relay 204. Relay 204 operates and disconnects the simplex dialing conductor from relay 205 and transfers it to ground through the ring conductor of the jack and plug and the impulse springs of the calling device CD^2 . Relay 204 also opens a point in the bridge across the tip and ring contacts of the line jack LJ^2 , so as to prevent this bridge from becoming

closed when relay 205 falls back responsive to being disconnected by relay 204.

The impulses are transmitted by the impulse springs of the calling device CD^2 as the dial thereof returns to its normal position. When the normal position is reached, relay 204 again falls back and relay 205, being reconnected, again operates.

The operator, after having dialed the complete number, may leave the plug P^2 in the jack DJ^2 or remove it as she sees fit.

When the called subscriber responds, the current flow over the conductors of the trunk line TL^2 is reduced in the manner explained in the above-mentioned Saunders application. When this takes place, the marginal supervisory relay 205 falls back and completes the bridge across the tip and ring conductors of the jack LJ^2 , whereupon the supervisory relay in the calling end of the cord circuit responds and extinguishes the associated supervisory lamp to give answered supervision. The two subscribers may now converse with each other.

When the called subscriber replaces his receiver upon the termination of the conversation, the current flow over the conductors of the trunk line TL^2 is restored to its normal value, whereupon relay 205 reoperates, resulting in the relighting of the supervisory lamp of the operator's cord circuit as a disconnect signal.

When the operator pulls down the connection upon perceiving the disconnect signal above mentioned, relays 202 and 203 fall back and relay 202 disconnects ground from the upper terminal of relay 205 whereupon relay 205 falls back also and the switches in the automatic office release responsive to the cessation of current flow over the conductors of the trunk line TL^2 .

What is claimed is:

1. In a telephone system in which automatic switches are operated from a manual switchboard to set up telephone connections, a trunk line outgoing from the manual switchboard to the automatic switchboard, a switch operating circuit including the conductors of said trunk line, means in said circuit for controlling the automatic switches to extend the connection, and means controlled over said circuit for initially closing a holding circuit for the automatic switches responsive to the response of the called subscriber and for opening said operating circuit.

2. In a telephone system, a trunk line divided into two sections and extending from a manual switchboard to an automatic switchboard, a switch operating circuit, means for dividing the trunk line into its two sections and for connecting said switch operating circuit to the second section, means for preparing a switch holding circuit including the two sections of said trunk line in series, and

means for automatically disconnecting said operating circuit from the second section and for uniting the two sections of the trunk line when a called subscriber responds to a connection set up under the control of said switch operating circuit.

3. In a telephone system, a trunk line extending from a manual switchboard to an automatic switchboard, a calling device at said manual switchboard, a normally open switch operating circuit including said calling device and said trunk line, a normally open switch holding circuit including said trunk line and excluding said calling device, and means responsive to the movement of said calling device off normal for completing said switch operating circuit and for preparing said switch holding circuit.

4. In a telephone system, a trunk line extending from a manual switchboard to an automatic switchboard, a calling device at said manual switchboard, a normally open switch operating circuit including said calling device and said trunk line, a normally open switch holding circuit including said trunk line and excluding said calling device, means responsive to the movement of said calling device off normal for completing said switch operating circuit and for preparing said switch holding circuit, and locking means for maintaining the said circuits closed and prepared, respectively, after the calling device has returned to its normal position.

5. In a telephone system, a plurality of trunk lines extending from a manual switchboard to an automatic switchboard, a plurality of calling devices at said manual switchboard for controlling automatic switches at the automatic switchboard over said trunk lines, means for connecting any one of said calling devices to any desired trunk line, and means for preventing a second calling device from being connected to any trunk line.

6. In a telephone system, a trunk line extending from a manual switchboard to an automatic switchboard, a calling device at the manual switchboard for controlling the automatic switches at the automatic switchboard, operator-controlled means for associating said calling device with said trunk line, a switch-control circuit including said trunk line, and means responsive to the off-normal movement of said calling device for connecting the calling device with the trunk line, and for initially closing said switch-control circuit, the switch-control circuit at this time including said calling device.

7. In a telephone system, a trunk line extending from a manual switchboard to an automatic switchboard, a calling device at the manual switchboard for controlling the switches at the automatic switchboard, means for associating said calling device with said trunk line, a relay individual to said calling

device for connecting the same with said trunk line when the calling device is moved off normal, and a holding circuit for said relay including a conductor individual to said trunk line.

8. In a telephone system, a trunk line extending from a manual switchboard to an automatic switchboard, a calling device at the manual switchboard having impulse contacts for controlling the switches at the automatic switchboard, means for associating the impulse contacts of said calling device with said trunk line, and means individual to said trunk line for connecting the calling device with said trunk line when the calling device is moved off normal.

9. In a telephone system, a trunk line extending from a manual switchboard to an automatic switchboard, a calling device at the manual switchboard for controlling the switches at the automatic switchboard, means for associating said calling device with said trunk line, and means including a connecting device individual to the calling device and another connecting device individual to the trunk line for connecting the calling device with the trunk line responsive to the calling device being moved from its normal position.

10. In a telephone system, a multi-position manual switchboard, a trunk line multiplied into several positions of said switchboard and extending to an automatic switchboard, a calling device at each of said positions associated with said trunk line, means for connecting any one of said calling devices with said trunk line, and means for preventing any calling device from being connected with said trunk line in case another calling device has already been connected therewith.

11. In a telephone system in which automatic switches are controlled by calling devices at a manual switchboard, a calling device having a test conductor and an operating conductor associated therewith, a normally open point in said operating conductor, and a relay controlled over said test conductor for preventing a closure of said normally open point.

12. In a telephone system in which automatic switches are operated by calling devices located at a manual switchboard, a calling device at a manual switchboard having associated therewith an operating conductor and a test conductor, a normally open point in said operating conductor, means for closing said normally open point responsive to an off normal movement of said calling device, and means for maintaining said operating circuit open in case a busy potential is on said test conductor, said means including a relay operated over said test conductor responsive to a busy potential thereon.

13. In a telephone system, a trunk line extending from a manual switchboard of the multiple position type to an automatic switch-

board, said trunk line being multiplied into a plurality of positions, a line jack and a dial jack for said trunk line at each of said positions, guarding means at said trunk line for placing a guarding potential on each of said dial jacks, said busying means being non-responsive to an insertion of a plug into a line jack and nonresponsive to the insertion of a calling device plug into the dial jack, and means associated with a calling device whose plug has been inserted into a dial jack for placing a guarding potential on the test contact of said jack, said guarding means at the trunk line being rendered effective for maintaining a guarding potential on said test contact until the plug has been removed from the line jack of the trunk line.

14. In a telephone system in which automatic switches are controlled by calling devices at manual switchboards, a signal individual to each calling device, a trunk line, two calling devices associated therewith, means for connecting one associated calling device with said trunk line, and means responsive thereto for operating the signal at the other associated calling device.

15. In a telephone system, in which a plurality of trunk lines extend from a multi-position manual switchboard in one exchange to an automatic switchboard in another exchange and in which each trunk line terminates at each position of the manual switchboard in a talking jack and in a dial jack, a plug-ending dial cord at each position including a dial-type calling device, a separate switch-control circuit for each trunk line including a talking conductor of the trunk line, and circuit arrangements whereby any calling device at any position may be inserted into the switch-control circuit of any trunk line through the associated plug and the auxiliary jack of such trunk line.

16. In a combined manual and automatic telephone system, a multi-position manual switchboard, a trunk line at one position of said board outgoing from a talking jack to an automatic switchboard at another exchange, an auxiliary dial jack at said position, a calling device at said position, means including a plug individual to said calling device for connecting said calling device with said dial jack, means for transferring the talking conductors of said trunk line from said talking jack to said dial jack, and separate multiple connections from each of said jacks to similar jacks at each of the other positions of said switchboard.

17. In a combined manual and automatic telephone system in which automatic switches are controlled over trunk lines extending from a manual switchboard and in which talking connections are made to a trunk line through the medium of a line jack and separate switch-control connections are made to such trunk line through the medium of a dial

jack auxiliary to the line jack, each jack having tip, ring, and sleeve contacts, the talking connections to the line jack being such that the talking conductors appear on the tip and ring contacts thereof, and connections between the talking conductors and the auxiliary jack such that one of the talking conductors instead of appearing on one of the other contacts of the said auxiliary jack appears on the sleeve contact thereof.

18. In a combined manual and automatic telephone system in which trunk lines outgoing from a manual switchboard to an automatic switchboard are each represented by a calling device jack, tip, ring, and sleeve contacts for each jack, a calling-device cord ending in a plug having corresponding contacts, and means including the sleeve of the plug and jack together with another contact of the plug and jack for completing a connection from the talking conductors of the trunk line to the calling device in the cord.

19. In a combined automatic and manual telephone system in which the automatic switches are controlled by the operator through the medium of a calling device included in a dial cord ending in a plug having tip, ring, and sleeve contacts and in which auxiliary jacks are provided, one for each trunk line, having contacts corresponding to the said contacts of the plug, and a switch-control bridge across the talking conductors of a connected trunk line including said calling device and the tip and sleeve contacts of said plug and the auxiliary jack of the trunk line.

20. In a combined automatic and manual telephone system in which a switch-controlling calling device is arranged to be associated with trunk lines, over which automatic switches are to be controlled, by means of a plug associated with the calling device and a jack associated with each trunk line, a switch-control circuit formed by the two talking conductors of any trunk line and the impulse springs of said calling device, said circuit including the tip and sleeve contacts of the plug and any jack into which it is inserted, and a test circuit including the ring contact of said plug and the corresponding contact of any cooperating jack.

21. In a combined manual and automatic telephone system in which automatic switches are controlled over a trunk line extending thereto from a manual switchboard, a calling device at said manual switchboard, means for associating said calling device with a particular one of said trunk lines while maintaining the outgoing conductors thereof in their normal condition, means responsive to an off-normal movement of the associated calling device for closing a switch-control circuit over said trunk line, means also responsive to the off-normal movement of said calling device for preparing a switch-holding

- circuit, means for subsequently disassociating said calling device from said trunk line, and means responsive thereto for opening said switch-control circuit and closing said holding circuit.
22. In a telephone system in which automatic switches are controlled over trunk lines extending thereto from a manual switchboard, said control being effected by interrupting a flow of direct current over a trunk line, there being no switch-control current flow over said trunk line normally, a calling device and means for associating it with any one of said trunk lines while maintaining the normal condition of such trunk line as to current flow, and means responsive to an off-normal movement of said calling device for setting up the said current flow in the associated trunk line.
23. In a combined manual and automatic telephone system in which trunk lines extend from a manual switchboard in one exchange to an automatic switchboard in another exchange and in which the switching mechanism in the automatic switch is prepared for operation by the setting up of a current flow over a trunk line, a calling device at said manual switchboard for interrupting the current flow to operate the automatic switches, means for associating said calling device with a particular one of said trunk lines while maintaining the state of no current flow in said trunk line, and means responsive to the off-normal movement of said calling device for setting up a current flow over the associated trunk line in order to prepare the switching mechanism at the automatic switchboard for operation.
24. In a combined manual and automatic telephone system in which trunk lines extend from a manual switchboard in one exchange to an automatic switchboard at the other exchange, and in which the automatic switching mechanism at said automatic switchboard is prepared for operation responsive to the establishment of a current flow over one of said trunk lines, a calling device at said manual switchboard, means for associating said calling device with one of said trunk lines, and means responsive to the off normal movement of said calling device for preparing said switching mechanism for operation by setting up a current flow over the associated trunk line.
25. In a combined automatic and manual telephone system in which trunk lines extend from a manual multi-position switchboard in one exchange to an automatic switchboard in another exchange, a calling device at each position of said manual switchboard for controlling the switching mechanism in said automatic switchboard over any one of said trunk lines, a line jack and an auxiliary calling-device jack for each trunk line at each position, a plug-ending dial cord at each position including the said calling device of such position, a signal at each calling device, and means responsive to the off-normal movement of any calling device when its associated plug is in the calling device jack of a trunk line for operating the signal associated with any other calling device which happens to be associated through the medium of its plug with the same trunk line at another position.
26. In a combined automatic and manual telephone system in which trunk lines extend from a manual switchboard in one exchange to an automatic switchboard in another exchange, a calling device at each position of said manual switchboard, a signal individual to each calling device, means whereby the operator at any position can associate said calling device with any one of said trunk lines, and means responsive to the off-normal movement of a calling device for operating the signal at any other calling device which happens to be associated with the same trunk lines at another position.
27. In a multi-office combined manual and automatic telephone system in which trunk lines extend from a multi-position manual switchboard in one exchange to an automatic switchboard in another exchange, a calling device at each position of said switchboard, means controlled by the operator at any position for associating her calling device with any one of said trunk lines, means responsive to the off-normal movement of a calling device for connecting such calling device to the trunk line with which it has been associated and means effective in case another calling device has been so connected previously for preventing the said connecting means from operating.
28. In a multi-office combined manual and automatic telephone system in which trunk lines extend from a multi-position manual switchboard in one exchange to an automatic switchboard in another exchange, a calling device at each position of said switchboard, means controlled by the operator at any position for associating her calling device with any one of said trunk lines, means responsive to the off-normal of a calling device for connecting such calling device to the trunk line with which it has been associated, means effective in case another calling device has been so connected previously for preventing the said connecting means from operating, a signal at each calling device, and a circuit for operating said signal when the said calling-device-connecting means is prevented from operating.
29. In a telephone system in which automatic switches are controlled by calling devices at a manual switchboard, a calling device, a line over which said calling device is arranged to control the automatic switches, means including a cord circuit for associating the calling device with the line, a relay in the

line and means for operating it to connect the calling device to the line, and means in the cord for shunting said relay to effect a disconnection of the calling device from the line.

30. In a telephone system in which automatic switches are controlled by calling devices at a manual switchboard, a calling device, a line over which said calling device is arranged to control the automatic switches, means including a cord circuit for associating the calling device with the line, a relay in the line and means for operating it to connect the calling device to the line, and a relay in the cord and means for operating it over the connected line to shunt the first named relay to effect a disconnection of the calling device from the line.

31. In a telephone system in which automatic switches are controlled by calling devices at a manual switchboard, a calling device and a relay associated therewith, a line over which the calling device is arranged to control the switches, a relay associated with the line, and a circuit arrangement for operating both relays to connect said calling device with the line through contacts of both relays in series.

32. In a telephone system in which automatic switches are controlled by calling devices at a manual switchboard, a calling device and a relay associated therewith, a line over which the calling device is arranged to control the switches, a relay associated with the line, and a circuit arrangement responsive to an operation of said calling device for operating both relays to connect said calling device with the line through contacts of both relays in series.

33. In a telephone system in which automatic switches are controlled by calling devices at a manual switchboard, a calling device and a relay associated therewith, a line over which the calling device is arranged to control the switches, a relay associated with the line, a circuit arrangement responsive to an operation of said calling device for operating both relays to connect said calling device with the line through contacts of both relays in series, and means including a polarized relay associated with said calling device for shunting the relay associated with the line to disconnect the calling device.

34. In a combined automatic and manual telephone system, a cord circuit having a calling device associated therewith for controlling automatic switching apparatus, a test relay in said cord circuit, off-normal contacts on said calling device, and circuit connections controlled by said contacts when the calling device is operated for disconnecting said test relay.

35. In a combined automatic and manual telephone system, a cord circuit having a calling device associated therewith for controlling automatic switching apparatus, a test

relay in said cord circuit, off-normal contacts on said calling device, and circuit connections controlled by said contacts when the calling device is operated for disconnecting said test relay and for substituting a guarding potential.

36. In a telephone system, a trunk line extending from a multi-position manual switchboard to an automatic switchboard, a line jack and a dial jack for said trunk line at each of a plurality of positions of said switchboard, a dial cord at each position arranged to be associated with said trunk line through a dial jack, a test relay in each cord, and means for controlling the test relay in any dial cord through a dial jack after a connection has been set up over a trunk line.

In witness whereof, I hereunto subscribe my name this 1st day of March, A. D. 1927.
